Primary Examiner — Elizabeth Albert*Assistant Examiner* — Kelley Donnelly(74) *Attorney, Agent, or Firm* — Gardner, Linn, Burkhardt & Flory, LLP(57) **CLAIM**

The ornamental design for the chair, substantially as shown and described.

DESCRIPTION

FIG. 1 is a perspective view of the chair according to the present invention;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan view thereof; and,

FIG. 7 is a bottom plan view thereof.

The broken lines showing in FIGS. 1-7 of the seat back and the design feature on the bottom of the chair in FIGS. 2, 3, 4, and 7 are included for the purpose of illustrating environment of the design and form no part of the claimed design.

The heavy black dotted line that defines the bounds of the claimed design forms no part thereof.
